Attorney.

UNITED STATES PATENT OFFICE.

JACOB EDWARD REMPE, OF KANKAKEE, ILLINOIS, ASSIGNOR OF ONE-FOURTH TO FRANK L. SHIDLER, ONE-EIGHTH TO LOUIS G. PAHNKE, AND ONE-EIGHTH TO WALTER G. CHILDS, ALL OF KANKAKEE, ILLINOIS.

OPERATING MECHANISM FOR WASHING-MACHINES.

No. 895,041.

Specification of Letters Patent.

Patented Aug. 4, 1908.

Application filed July 30, 1907. Serial No. 386,282.

To all whom it may concern:

Be it known that I, JACOB EDWARD REMPE, a citizen of the United States of America, and a resident of Kankakee, in the county of 5 Kankakee and State of Illinois, have invented certain new and useful Improvements in Operating Mechanisms for Washing-Machines, of which the following is a specification.

10 This invention relates to that type of washing machines in which a revoluble pronged dasher is given a reciprocating rotary motion on a vertical axis within the tub or housing of the apparatus. And the present invention has for its object to provide a simple and efficient structural formation and arrangement of the driving mechanism in which the heavy fly-wheel generally employed is housed in a safe and compact manner and entirely out of the way, and with which a very high speed of the fly-wheel is attained during the normal speed of the operating mechanism with a consequent uniform and easy operation of the apparatus, all as 20 will hereinafter more fully appear.

In the accompanying drawings:—Figure 1, is a vertical sectional elevation of a washing machine embodying the present improvement. Fig. 2, is a detail bottom view of the 30 fly-wheel and its operating mechanism.

Similar numerals of reference indicate like parts in both views.

Referring to the drawings, 1 represents the tub or casing of the apparatus, preferably 35 of the cylindrical form shown. Such tub has the usual hinged top or cover 2, and closed bottom 3 surrounded by the usual marginal flange or chime 4, as shown.

5, is the stirrer arranged in the interior of 40 the tub and consisting of a dish shaped body portion provided with a series of downwardly projecting stirrer prongs 6, and mounted by means of a non-circular central bore upon a similarly formed driving hub, hereinafter described, so as to rotate therewith and at the same time be capable of an independent rise and fall movement in accordance with the amount of clothes being washed.

7, is a non-circular hub above referred to, 50 and which is formed with a stop collar on its lower end to limit the fall movement of the stirrer aforesaid.

8, is a vertical stirrer carrying shaft jour-

naled in the bracket bushing 9 attached to the cover 2 of the tub, and carrying at its 55 lower end the hub 7 aforesaid, and at its upper end the spur pinion 10 of the driving gear.

11, is a horizontal reciprocating rack bar arranged immediately above the top 2 of the 60 tub, and meshing with and driving the pinion 10 aforesaid.

12, is a vertically arranged operating hand lever pivoted near its mid-length to the side of the tub 1, with its upper portion operatively connected to the rack bar 11 as shown.

13, is a horizontal pitman connected at one end by a suitable universal joint 14 with the lower end of the operating lever 12; and at the other end such pitman is fixedly attached 70 to a shaft 15 journaled in the free end of a crank arm hereinafter described.

16 is a vertical journal stud secured centrally to the bottom of the tub, and provided with a bearing collar 17 intermediate its 75 height as shown.

18, is a horizontally arranged fly-wheel of a diameter somewhat less than that of the tub, and located in the cavity at the underside of said tub, formed by the flange or chime 4. Such fly-wheel is journaled on the shaft 16 above the bearing collar 17, and the bearing between the hub of the fly-wheel and the collar 17 is preferably of the ball type, as shown.

19, is a pinion having a fixed connection to the fly-wheel 18, and meshing with and receiving motion from a gear wheel 20 keyed or otherwise secured on the upper end of the shaft 15 aforesaid.

21, is the crank arm, above referred to, journaled loosely upon the journal stud 16 below the bearing collar 17 aforesaid and provided at its outer end with a vertical tubular bearing for the shaft 15 aforesaid.

In the operation of the above described fly-wheel mechanism, the gear wheel 20 has an orbital travel around the axis of revolution of the crank arm 21, and being held from rotation on its own axis by a rigid connection to the pitman 13 is adapted to impart to the pinion 19 and to the fly-wheel 18 a high speed adapted to render the operation of the other portions of the mechanism easy and uniform.

Having thus fully described my said in-

vention what I claim as new and desire to secure by Letters Patent is:

In an operating mechanism for washing machines, a support 3 a spider attached to the underside of said support and provided with a depending journal stud, a horizontal fly wheel journaled on said stud, an operating lever, intermediate gearing between said lever and the fly wheel for imparting increased speed thereto, the same comprising a pinion carried by the fly wheel, a crank arm journaled on the aforesaid journal stud below the fly wheel, a shaft journaled in the

outer end of said crank arm, a gear wheel on the upper end of said shaft and in mesh with the pinion of the fly wheel, a pitman connection at the lower end of said shaft and a pitman connected to said pitman connection and to the operating lever aforesaid, substantially as set forth.

Signed at Kankakee, Illinois, this 24 day of July, 1907.

JACOB EDWARD REMPE.
